UNITED STATES PATENT OFFICE.

CHARLES FRANKLIN WRIGHT, OF KENNEDY, MISSOURI.

BREEDER'S APPLIANCE.

1,111,935.

Specification of Letters Patent. Patented Sept. 29, 1914.

Application filed March 28, 1914. Serial No. 828,019.

To all whom it may concern:

Be it known that I, CHARLES FRANKLIN WRIGHT, a citizen of the United States, residing at Kennett, in the county of Dunklin and State of Missouri, have invented certain new and useful Improvements in Breeders' Appliances, of which the following is a specification, reference being had to the accompanying drawings.

10 This invention relates to new and useful improvements in breeders' appliances and more particularly to a tail pad for application to the tail of the female animal and the main object of the invention is the provision 15 of an appliance of this character which is so arranged upon the animal's tail as to prevent a misplaced entry.

Another object of the present invention is the provision of an appliance of the above 20 character which will possess advantages in points of efficiency and durability, is inexpensive to manufacture and, at the same time is simple in construction and operation.

With the above and other objects in view, 25 the invention consists in the novel features of construction and the combination and arrangement of parts as will be hereinafter referred to and more particularly pointed out in the specification and claims.

30 In the accompanying drawing forming a part of this application, Figure 1 is a detail perspective view illustrating the application of my improved appliance; and Fig. 2 is an enlarged detail perspective view illustrating the device as about to be applied.

In the construction of my improved appliance, I form a removable bandage which is generally indicated by the numeral 1 and is preferably constructed of a single piece 40 of double thick material having a pocket 2 formed at one end. The longitudinal edges of the bandage are provided with the spaced openings 3, which are adapted for the reception of the lacing string 4, whereby the bandage can be tightly laced upon the tail 45 of the animal as shown in Fig. 1. The inner end of the bandage is provided with an enlarged circular portion 5 which is adapted to be arranged around the inner enlarged 50 end of the animal's tail and is held securely

in position by means of the strap 6 and the buckle 7 which are secured to opposite sides of the bandage 1.

Arranged within the pocket 2, is a ball of soft material which entirely fills the 55 pocket. The pocket after being filled with the material forms a spherical projection which, when the bandage is placed in position, is adapted to be arranged tight up against the animal's rectum and entirely 60 close the same, thus entirely preventing a misplaced entry.

From the above description taken in connection with the accompanying drawing, it will be readily apparent that I have provided a simple and durable appliance of the above character which can be quickly and readily applied to the tail of the animal. By the use of the strap 6 and the buckle 7 and the lace 4, it will be apparent that the 70 bandage can be readily applied to the animal's tail and prevent the interference of the hair or articles which might be clinging to the animal's tail. It will also be apparent that I have provided a simple and durable 75 device which can be manufactured and placed upon the market at a comparatively low cost.

While I have shown and described the preferred form of my invention, it will be 80 apparent that various changes in the details of construction and in the proportions may be resorted to for successfully carrying my invention into practice, without sacrificing any of the novel features of construction or departing from the scope of the appended 85 claims.

Having thus described this invention, what I claim is:—

1. A device of the class described including a bandage, means for detachably connecting the longitudinal edges thereof, said bandage having a pocket at one end thereof, and means arranged within said pocket forming a spherical projection as and for 95 the purpose set forth.

2. A device of the class described including a bandage formed of double thick material having a pocket formed in one end thereof, means detachably connecting the 100

longitudinal edges thereof, a substantially circular enlarged portion formed contiguous with the pocket, means for connecting the open sides of the enlarged portions, and
5 means arranged within said pocket forming a spherical projection, as and for the purpose set forth.

In testimony whereof I hereunto affix my signature in the presence of two witnesses.

CHARLES FRANKLIN X WRIGHT.
